TONE ARM

Roy Dally, Racine, Wis., assignor to Webster Electric Company, Racine, Wis., a corporation of Delaware

Original application January 18, 1941, Serial No. 374,964. Divided and this application October 18, 1942, Serial No. 462,276

4 Claims. (Cl. 274—1)

The present invention relates to tone arms, and is particularly concerned with improvements in the free end of the tone arm whereby the stylus securing screw may be concealed, though accessible for removal or insertion of the stylus when necessary.

One of the objects of the invention is the provision of an improved tone arm construction having a pickup provided with a chuck having a stylus securing screw, the head of which is suitably concealed inside the tone arm, but which is adapted to be uncovered for engagement with the screw driver.

Another object of the invention is the provision of an improved handle structure for use in lifting the tone arm to remove it from a record or place it on a record.

Another object of the invention is the provision of an improved handle structure for tone arms, which is also adapted to be removed from the tone arm for exposing the stylus securing screw whereby the screw may be concealed, yet made accessible to those who are familiar with its location and with the structure of the tone arm.

Another object of the invention is the provision of an improved tone arm having a removable handle, which is adapted to permit the tone arm to be lifted more conveniently for application to a record or removal from a record.

The present application is a division of my prior application, Ser. No. 374,964, on Tone arms, filed January 18, 1941, now Patent No. 2,313,126, granted March 9, 1943.

Other objects and advantages of the invention will be apparent from the following description and the accompanying drawing, in which similar characters of reference indicate similar parts throughout the several views.

Referring to the single sheet of drawings,

Fig. 1 is a top plan view of a phonograph equipped with a tone arm embodying my invention;

Fig. 2 is a fragmentary sectional view, taken on the plane of the line 2—2 of Fig. 1;

Fig. 3 is a bottom plan view of the tone arm structure, with the lower pickup parts removed, showing the structure of the handle for the tone arm.

Referring to Fig. 1, 28 indicates the fixed support for the tone arm 21 and the turntable 22 in the form of the top panel of a phonograph or other housing. The tone arm, which is indicated in its entirety by the numeral 21, includes a pivotal supporting member 23, by means

of which the tone arm is mounted for substantially universal movement, so that it can be lifted from the record and so that it can progress across the record as its needle follows the groove in the record 24.

5 The tone arm is preferably of a channeled construction, having an upper wall 25 (Fig. 6) and a pair of depending side walls 26 and 27 joined by the partially cylindrical corner portions 28. At its rear or pivotally supported end, it has an end wall 29, closing the end of the channel and joined to the top wall 25 by a partially cylindrical portion 30.

10 The free end of the tone arm is preferably provided with an enlargement for receiving the crystal pickup, and this enlargement is bordered by a depending wall 38, which may be substantially cylindrical at the end 39 of the tone arm.

15 In the particular embodiment selected to illustrate the invention, the tone arm has formed integrally with it the half housing 40, which forms the upper part of the crystal pickup, the lower half housing being of metal, indicated at 41.

20 23 Other forms of pickup may also be employed, and the handle may also be utilized on other forms of tone arms.

25 The pickup is provided with a chuck 42, having a threaded bore 43 for receiving a threaded screw bolt 44. The bore 43 communicates with the stylus socket 45, which is adapted to receive the shank of the stylus 46. The stylus is secured in place by means of the screw bolt 44, the head of which has a suitable socket 47. The socket 35 may be a slot for an ordinary screw driver, or a cruciform slot for special screw drivers.

30 In the preferred form of the invention the chuck has a thrust bearing 48 engaging a complementary thrust bearing surface 49, and the 40 trunnion 50 is surrounded by a rubber sleeve 51, which also extends between these thrust surfaces.

35 One of the difficulties in the use of a screw driver on such a delicate instrument is that too much force will be applied, and the present tendency is toward the use of permanent stylus which are not intended to be removed by the ordinary user of the tone arm.

40 Thus it is desirable that the head 52 of the 50 screw be concealed, yet accessible for removal of the stylus, if it is absolutely necessary.

45 For this purpose the end wall 39 is provided with an upwardly extending slot 53, having parallel side walls; and this slot is of sufficient 55 width to pass the shank of a small screw driver

engageable in the socket 47 of the head 52 of the screw bolt 48.

The slot 53 may be closed by means of the handle 54. The handle 54 may comprise a cast metal member or a member molded of a phenolic condensation product, or other suitable material. It is provided with a securing portion 55 and a finger engaging portion 56. The finger engaging portion 56 is preferably concavely curved on its lower side at 57, and is convexly curved at 58 on its upper side.

The upper side may have a reinforcing rib 59 bordered by longitudinally extending curved or grooved portions 60, 61. The extreme end portion 62 may be reversely curved to extend upward, and all the portions of the handle 54 are preferably slightly rounded.

The securing portion of the handle, comprising a substantially rectangular portion 55, has a pair of parallel slots 63, 64 on the opposite sides of this portion. The slots 63, 64 are wide enough to receive the end wall 39, and the body portion between the slots is slightly less than the width of the slot 53 in the end wall.

Thus the handle securing portion 55 may be slid upward in the slot 53, and the wall portions 39 will extend into the slots 63, 64. The handle should have such a fit that it is frictionally held in place.

It will thus be observed that this handle may be conveniently removed whenever it is desired by the repairman or the manufacturer of such tone arms, and the stylus may be secured or removed, but the stylus will ordinarily not be disturbed by the user of the tone arm.

The handle is adapted to be used for lifting the tone arm by placing one or two fingers under it, and there is less likelihood of the tone arm being dropped than if no handle is provided.

Unauthorized persons will not ordinarily tamper with the stylus or try to change it under these conditions, and it is believed that better service may be secured by having these parts accessible only to those familiar with the tone arm. There is less likelihood of sufficient axial force being placed on the screw to damage the crystal.

In the embodiment illustrated such force is resisted by the thrust bearings, but the present handle and tone arm structure may be used upon pickups not having thrust bearings.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. In a tone arm, the combination of a re-

producer unit carried by the free end of said tone arm with a channeled member of molded insulating material having depending side and end flanges, the flange at the free end of said tone arm having an inwardly extending slot open at its lower end, and a handle having a body receivable in said slot and having thrust surfaces engaging on the inside and outside of said tone arm.

2. In a tone arm, the combination of a channeled tone arm member having a downwardly open socket at its end for receiving a pick-up unit, with a pick-up unit in said socket, said pick-up unit having a chuck provided with a stylus socket, and having threaded means for engaging a stylus in said socket, said tone arm being formed with an aperture in its side wall opposite said threaded means for passage of a tool, and means for closing said aperture, comprising a removable handle adapted to be secured in said aperture, said aperture having parallel walls and being open at the bottom, and said handle having a slideable portion for engaging the edges of said walls in said aperture, and said handle having oppositely located slots for receiving the wall portions adjacent said aperture.

3. In a tone arm, the combination of a tone arm comprising a channeled member having depending side and end flanges, and the flange at the free end of said tone arm having an upwardly extending slot open at its lower edge, with a handle member comprising an outwardly extending finger piece adapted to be engaged by the fingers, and a securing body, said securing body having formed on its opposite sides a pair of vertical slots, said slots being of sufficient thickness to receive said depending flanges at the side, the flanges of said tone arm at said upwardly extending slot, and to be secured to said tone arm by frictional engagement.

4. In a tone arm, the combination of a tone arm comprising a channeled member having depending side and end flanges, and the flange at the free end of said tone arm having an upwardly extending slot open at its lower edge, with a handle member comprising an outwardly extending finger piece adapted to be engaged by the fingers, and a securing body, said securing body having formed on its opposite sides a pair of vertical slots, said slots being of sufficient thickness to receive said depending flanges at the side, the flanges of said tone arm at said upwardly extending slot, and to be secured to said tone arm by frictional engagement, a reproducer unit in said tone arm, said reproducer unit having a chuck with a threaded member for engaging a removable stylus, said reproducer unit being so located that said threaded member is accessible through said upwardly extending slot in the depending flanges of said tone arm.

ROY DALLY.
